DECORTICATING MACHINE

Joseph Julius Mareczak, Bigpoint, Miss.

Application October 17, 1938, Serial No. 235,533

15 Claims.

(Cl. 19—11)

This invention relates to a machine for decortinating ramie stalks.

It has been proposed to treat the bark of the ramie stalks with a chemical for removing the gum and for causing disintegration of the bark to recover the fibres by means of a chemical solution and in connection with mechanical means. However, during the chemical treatment the fibres are affected by the chemicals in the solution so that not only a disintegration of the bark is accomplished, but the fibres themselves are acted on to such an extent that they are marred which causes weakening of the fibres. Very frequently in this type of process the fibres are thoroughly washed after the chemical treatment and then dried so that the fibres assume a brittle condition and are readily broken.

It is an object of the present invention to provide a purely mechanical process for obtaining the fibres from the bark of the ramie stalks after the stalks are boiled in clear water after which the stalks are placed longitudinally upon an elongated machine where they are clamped in position upon a table and moved toward a movable clamping device which will fix the larger ends of the stalks to a traveling base member so that when the member is moved away from the clamping table the woody portions of the stalks or core are withdrawn from the bark which is maintained in position by the uniform pressure upon the bark so that the stalks are withdrawn from the bark. However, the bark is then passed between rollers having a surface sufficiently roughened which will remove the outer dark bark. The bark which has thus been stripped is then placed in vats and boiled in clear water to remove not only the gum but also the coloring matter, the fibres being then washed if necessary in a soapy solution or clear water whereby clear white fibres are obtained.

Another object of the invention is the provision of a machine having means for clamping a plurality of stalks in juxtaposition while maintaining uniform pressure on the stalks so that when the stalks are moved to a device for gripping the larger ends of the stalks and this device is moved away from the clamping means the stalks will be withdrawn from the bark which is maintained in a fixed clamping position in the clamping means, the clamping means being moved towards the gripping device by either a manually or power driven mechanism, the gripping device being moved with uniform speed away from the clamping means when the stalks are being withdrawn from the bark.

A further object of the invention is the provision of a machine for distintegrating ramie stalks, in which the stalks are uniformly clamped in position on a movable table of the machine so that when the woody portions of the clamped stalks are moved longitudinally of the machine by a gripping device the woody portions of the stalks will be withdrawn from the clamping table leaving the bark in its initial position on the table, the gripping device being so constructed that when the ends of the bark covered stalks are forced between a pair of jaws of the gripping device the bark will be pushed backwardly after which the jaws of the gripping device are moved to an operative clamping position on the free ends of the woody portions of the stalks, a pair of rollers having the surfaces roughened applying pressure to the bark when the bark is drawn through said rollers after the woody stalks have been removed in order to roughen the surface of the bark so that the dark exterior portions of the bark will be loosened and removed before the bark is placed in vats containing clear water for the removal of gum and other foreign matter from the fibres, the gripping device when moved into engagement with the inner free ends of the stalks raising one of the rollers and retaining the same in an inoperative position.

This invention will be best understood from a consideration of the following detailed description, in view of the accompanying drawings forming a part of the specification, nevertheless; it is to be understood that the invention is not confined to the disclosure, being susceptible of such changes and modifications as define no material departure from the salient features of the invention as expressed in the appended claims.

In the drawings:

Figure 1 is a longitudinal plan view of my decortinating machine.

Figure 2 is a longitudinal side view of the same.

Figure 3 is a transverse section taken along the line 3—3 of Figure 1.

Figure 4 is a transverse section taken along the line 4—4 of Figure 1.

Figure 5 is a transverse section taken along the line 5—5 of Figure 1.

Figure 6 is a side view of a portion of the machine showing the transmission for a reverse movement or a forward movement of the gripping devices which pull the stalks from the clamped bark.

Figure 7 is a view in perspective of the bottom element of the gripping device for aiding in

holding the stalks when the stalks are pulled from the bark.

Figure 8 is a view in perspective of the upper gripping jaws.

Figure 9 is an enlarged vertical longitudinal section taken along the line 9—9 of Figure 1.

Figure 10 is an enlarged vertical section showing the gripping jaws in engagement with the ends of the stalks just before the stalks are withdrawn from the bark.

Figure 11 is a fragmentary vertical section in the neighborhood of the gripping jaws showing the jaws in further movement away from the clamping table.

Figure 12 is a fragmentary vertical section similar to that shown in Figure 11 showing the advanced stage of the withdrawal of the stalks from the bark.

Figure 13 is an enlarged vertical section similar to that shown in Figures 11 and 12 showing the clamping table being moved away from the gripping jaws with the removed bark being drawn between a pair of rollers.

Figure 14 is an enlarged vertical section similar to that shown in Figures 11 to 13, inclusive, disclosing the bark being withdrawn from the clamping member.

Figure 15 is a fragmentary enlarged vertical section showing the advanced stages of the withdrawal of the bark.

Figure 16 is a horizontal section taken along the line 16—16 of Figure 3.

Figure 17 is a vertical section taken along the line 17—17 of Figure 1.

Figure 18 is a fragmentary vertical longitudinal section showing the automatic connection between a removable gripping jaw and a base member supporting a pivoted jar.

Referring more particularly to Figures 1 and 2, it will be seen that a pair of longitudinally disposed beams 20 and 21 are located at each side of the machine and these beams are supported by legs 22, 23 and 24. The beams at their opposite ends are connected by means of bars 25 located at each end of the frame.

A pair of spaced angle irons 30 have one flange 31 secured to the inner face of a beam 20 or 21, while the other flange 32 extends outwardly at right angles to the first mentioned flange and 50 forms a track for a clamping table generally designated by the numeral 33.

The table 33 is provided with depending brace bars 34 and 35. The bars 34 are provided with rollers 36 which rest on the flanges 32 of the angle irons 30.

A rack 37 is secured to the bottom of the bar 35 and meshes with a gear wheel 38 which is fixed to a shaft 39. This shaft has bearings 40 which are secured to the bottom face of the beams 20 and 21. A crank 41 is secured to the outer end of the shaft whereby the shaft may be manually rotated.

Bars 43 extend upwardly from the opposite ends of the clamping plate 42 and are rigidly secured to said plate. A rod 44 is secured to the upper edge of each bar 43 and extends beyond the opposite ends of said bar. One end of each rod shown at 45 (Fig. 3) is provided with a hook adapted to engage over a rod 46 for supporting the clamping plate 42 in a horizontal position. The opposite end of each rod 44 is provided with a bearing 47 that is received by a rod 48. A handle 49 secured to the outer face of the plate 42 provides means for raising one end of the plate so that it will swing upon its

bearings 47 on the rod 48 whereby the plate may be raised from the table 33.

It will be noted that the bottom face 50 of the plate 42 is roughened or corrugated and the upper surface of the table 33 is likewise roughened or corrugated as shown at 51 in order to provide for frictional gripping upon the bark of the stalks.

The rods 46 and 48 are secured to vertically disposed bars 55 and 56 and these rods are slidably mounted respectively in bearings 57 and 58 secured to the outer faces of the legs 23 to provide for reciprocation of the rods 55 and 56 at opposite sides of the frame so that the clamping plate 42 may be elevated or lowered as will be presently explained.

A pair of latch members 60 are pivotally mounted at 61 on the under face of the rods 44 adjacent the movable end of the plate 42 and are adapted to be moved by means of pivotally mounted handles 52 beneath the rod 48 for locking the clamping plate to the rod.

A pair of rods 63 are located adjacent each bearing 57 or 58 at opposite sides of the frame and these rods at their upper ends are provided with hooks 64 which engage over the respective rods 46 and 48.

An I-shaped frame generally designated by the numeral 65 consists of a pair of end bars 66 and a transverse bar 67. The bars 66 are located longitudinally of the frame and between the legs 23 at each side of the frame. The ends of the transverse bar 67 are rigidly secured to the intermediate portions of the bars 66. The frame is adapted to be reciprocated vertically in a manner which will be presently described.

Four rods 68 have their upper ends bolted as shown at 69 to the end of the bars 66 and these rods or wires extend downwardly toward a common center and each wire is provided with an eye 70 received by a bolt 71 carried by the upper ends of the links 72 which are pivotally connected at 73 with a lever 74.

It will be noted that the lower ends of the rods 68 have right angular portions 75 which are bolted at 76 to the ends of the side bars 66.

A lever 74 is pivotally mounted at 77 on one side of the frame and extends to the opposite side and projects beyond the same as shown at 78 to form a treadle. A U-shaped member 79 embraces the treadle 78 and is secured thereto as shown at 80. An operating arm 81 with a pawl 82 is pivotally mounted at 83 within the bight portion of the U-shaped member 79. The free end of the pawl is adapted to engage a rack 84 carried by the reinforcing beam 85. It will be noted that a reinforcing beam is located at each side of the frame and connected between the legs 23. A spring 86 urges the member 81 upwardly so that the pawl 82 engages the teeth of the rack 84 and maintains the treadle 78 and the lever 74 in a lowered position when the lever is depressed until released by the pawl 82.

A spring 86 is located in each guide member (Figs. 2 and 3) which at all times urges the rods 47 upwardly for raising the clamping member 42 out of engagement with the table 33.

In Figure 1 it will be seen that the ramie stalks 90 extend beyond the ends of the table and the clamping member 42 and the table is longer than the clamping member. However, the inner ends of the stalks as shown in Figure 1, extend only slightly beyond the inner end of the table 33.

A pair of chain belts 91 are carried by a pair of sprockets 92 at the outer end of the machine 75

and these sprockets are secured to a shaft 93 which carries a roller 94. The inner ends of the chains are trained on sprockets 95 and 96 secured to a shaft 97 or shaft 97^a. A gear wheel 98 is secured to one end of the shaft 97 outwardly of the sprocket 95 and is adapted to be rotated manually by means of a crank 99.

A gear 100 mounted upon a stub shaft 101 which is carried by a vertically disposed bar 102 secured to the right hand side of the frame in Figure 1 and more particularly shown at the left hand side in Figure 4, meshes with the gear 98. A gear 103 is secured to the inner end of the shaft 101 and at the inner face of the bar 102 (Figs. 4 and 6).

A gear 105 is secured to the inner end of a shaft 106 to which is secured a pulley 107 driven by a power belt 108.

A bell crank lever 110 is pivotally mounted on a shaft 101 and is provided with an operating rod 111 at the lower free end for oscillating the bell crank. An arm 112 of this bell crank is provided with an angular extension 113 upon which is rotatably mounted a gear 114 adapted to mesh with the gear 105. At the junction between the arm 112 and the extension 113 is mounted a shaft 115 upon which is rotatably mounted a gear 116 which is adapted to mesh at certain times with the gear 103 and with the gear 105. The gear 114 is always in mesh with the gear 116.

In Figure 6 the gears 114 and 116 are respectively in mesh with the gear 105 and the gear 103. When the lower arm of the bell crank lever 110 is moved in the direction indicated by the arrow in Figure 6, the gear 116 will roll on the gear 103 and be brought into mesh with the gear 105, while the gear 114 will be moved out of mesh with the gear 105 so that it will idly revolve when the gear 116 directly connects the gears 103 and 105. This arrangement is such that when the gears 103, 105 and 116 are in mesh the gear 103 will be revolved in one direction while when the bell crank lever 110 is moved in the opposite direction, as indicated by the arrow in Figure 6, the gears will be in the position shown in Figure 6 and the gear 103 will be reversely rotated. This arrangement has been provided so that the chain 91 can be moved in opposite directions for a purpose which will be presently explained.

A device is provided generally indicated by the numeral 120 (Fig. 1) for gripping the inner ends of the stalks 90 so that the stalks per se may be drawn in the direction indicated by the arrow in Figure 1 away from the clamping table 33 so that the bark of the stalks will be held by the clamping table after the woody portion of the stalks have been removed.

This clamping arrangement consists of a jaw 121 (Fig. 8) which is carried by a pair of arms 122 and these arms are connected by a bight portion 123 at their outer ends. These arms are pivotally mounted (Figs. 10 and 11) on a shaft 24 on the upper ends of brackets 125 which are secured to a table 126 extending transversely of the frame.

The table is secured to the longitudinally disposed endless chains 91 by means of arms 127 which extend laterally from the ends on the table and are secured as shown at 128 to the chains. Thus, it will be seen that as the chains are moved in the direction of the arrow as shown in Figure 1, the table will likewise be carried along with the chains. The outer ends of the table 126 are located in slots 129 formed in the beams 20 of the frame so that the table will be moved in a hori-

zontal plane when it is drawn along the frame by the chains.

A plurality of complementary clamping jaws 131, 131^a and 131^b are placed in superimposed relation at one side of the shaft 97. The upper faces of each of these jaws are corrugated as shown at 132 as is the under face of the jaw 121 as shown at 133^a (Figs. 7 and 8). The ends of these jaws as shown in Figures 9 to 11, inclusive, are located in guides 133 secured to the inner face of the side bars 20 (Fig. 4). The rear walls 134 of these guides (Figs. 10 and 11) are shorter than the front wall so that these movable clamping jaws 131 may be withdrawn from the guides when the upper ends of the guides are open. Each of the guides includes a rear wall 134, a front wall 135, bottom 136 and side walls 137. A coil spring 138 rests upon the bottom 136 in each guide and these springs tend to force the superimposed movable jaws 131 outwardly of the guides and towards the jaw 121.

The rear wall 134 of each guide is provided with a slot through which rides an arm 140 and a catch 141 is formed on the end of each arm adapted to engage a catch 142 which projects from the front end of the table 126. It will be noted that there is a catch adjacent each end of the clamping jaw 131 and at each end of the table 126. The slots are indicated by the numeral 143 (Fig. 9).

Each of the clamping jaws 131 are provided with grooves 145 in the bottom face thereof and adjacent the catches 141. These grooves are adapted to receive projections 146 (Figs. 9 and 16) extending from the front end of the table 126 for supporting the jaws 131 when the table 126 is moved longitudinally of the frame and when the jaws 131 are drawn along with the table by the catches 141 and 142. The opposite ends of the jaws 131 are guided within grooves 147 formed in the longitudinal side beams 20. The ends of the table 126 are also guided in these grooves so that the jaw 131 will be maintained in longitudinal alignment with said table.

The jaw 121 is maintained in gripping relation with the ends of the woody portions of the stalks 45 by means of pawls 150 which are pivotally connected at 151 to the arm 122 of the U-shaped member (Fig. 9). These pawls have pivotal connections at 152 with arms 153 of the second U-shaped member 154. The last mentioned U- 50 shaped member is slideable in guides 155 secured to the arms 122. A spring 156 is connected to the bight portion of the U-shaped member 154 and the opposite end of the spring is connected to a rod 157 which is in turn connected to the shaft 55 124 upon which the arms 122 are pivotally mounted. The spring 156 tends to pull the U-shaped member 155 inwardly for maintaining the free ends of the pawls 150 in engagement with teeth of a pair of racks 158 which are located below 60 the free ends of said pawls. Thus, it will be seen that when the U-shaped member 122^a is forced to its uppermost position the jaw 121 will be clamped onto the ends of the stalks and the ends of the stalks will be clamped between the jaws 65 121 and 131.

Springs 160 which are connected between the U-shaped member 122^a and the table 126 will pull down on the U-shaped member when the pawl 150 is out of engagement with the teeth of the 70 rack 158 and maintain the jaw 121 in open position.

A pair of rollers 165 and 166 are mounted adjacent the guides for the jaws 131 and in spaced relation therewith. The roller 165 is carried by 75

a pair of arms 167 and these arms are pivotally mounted in the vertical bars 102. The outer ends of the arms 167 carries a shaft 168 upon which the roller 165 is secured.

5 One end of the shaft 168 is provided with a gear 169 which meshes with a gear 170 mounted on a stub shaft 171 carried by the side frame so that when the gear 170 will be revolved the roller 165 will likewise be revolved when the gear 169 10 is in its lowermost position and in meshing relation with the gear 170. A crank 172 is secured to the gear 170 for manually rotating the gear when desired.

15 A gear 175 secured to a shaft 176 is in mesh with the gear 170 and a gear 177 is secured to the inner end of the shaft 176 and is adapted to revolve said shaft. A gear 178 is secured to a shaft 179 and this shaft in turn is revolved by a pulley 180 driven by a belt 181.

20 A pair of gears similar to the gears 114 and 116 together with a bell crank 110 and its operating parts are associated with the gears 177 and 178 in a similar manner to the association of the gears 103 and 105 with the gears 114 and 116 so

25 that the gear 177 may be revolved and likewise the gear 175 in opposite directions for rotating the gear 170 in opposite directions for a purpose which will be presently explained. Shafts 176 and 179 are carried by a vertically disposed bar 182.

30 On the outer end of a shaft 185 which drives a roller 166 is secured a gear 186 which meshes with a gear 187 secured to the shaft 168 whereby the roller 166 will be driven when the roller 165 is revolved when the roller 165 is in its lowermost position.

35 A pair of inclined rods 188 are carried by the table 126 and are adapted to have their inner ends so positioned that they will move between the rollers 165 and 166 and as the table 126 is moved to the left in Figure 9 the upper rollers 165 will be raised and supported by the arms 167. The object of raising the rollers at this time is to place the roller 165 in a position so that the 40 clamping jaw 121 may be properly positioned with respect to the clamping jaw 131 for clamping the ramie stalks to the table. The various movements of the roller 165 are shown in Figures 45 9 and 10.

40 Referring more particularly to Figure 3 it will be seen that a rest or support 190 is secured to the side of the supporting frame for the machine and adjacent the movable clamping member 42 so that when the clamping member is elevated it 45 can be moved backwardly against the support and retained in position while the stalks are being placed upon the clamping table 33.

45 The operation of my device is as follows: The ramie stalks are cut while the bark is green and 50 they are placed in vats where the stalks are boiled in pure water until the bark becomes completely loose on the woody portions of the stalks. They are then removed from the vat and placed on the clamping table 33 while still moist and the 55 top clamping member 42 is then lowered away from the rest 190 until the hooks 45 of the bars 44 rest upon the bar 46. The latches 60 are then moved into locking position for connecting the clamping member 42 to the bar 46. After 60 this the treadle 78 is then depressed as will be the lever 74 and the rods or wires 68 will pull downwardly upon the I-beam 65 and cause the clamping member 42 to exert pressure on the stalks on the table 33.

65 75 The crank 14 is then revolved as will be the

shaft 39 so that the gear wheel 38 will move the rack 37 and likewise the table 33 towards the gripping device composed of the pivoted jaw 121 and the uppermost removable jaw 131 midway of the machine. The jaw 121 is normally elevated by the action of the spring 160 which pulls downwardly on the U-shaped member 122a. As the inner ends of the stalks are forced between the jaws the bark on said stalks is forced rearwardly so that when the U-shaped member 122a 10 is elevated the jaw 121 will be forced downwardly on to the woody portion of the stalk and the pawl 158 will retain the jaw 121 in clamped position on the stalks.

15 It will be appreciated that the U-shaped member 122a must be moved towards the left in Figs. 1 and 2 until the jaw 121 is located directly above the jaw 131. When the U-shaped member is being moved to this position the inclined member 188 (Fig. 9) will engage the ends of the shaft 168 20 and thus raise the roller 165 out of operative relation with the roller 166.

25 The stalks are now in position to be drawn towards the right in Figs. 1 and 2 for pulling the woody portions of the stalks away from the bark 25 which is clamped on the table 33.

30 Referring more particularly to Figs. 5 and 6 it will be seen that it is necessary to oscillate the bell crank lever 110 so that the various gears 103, 116 and 105 will be in meshing relation for causing rotation of the shaft 97 and movement of the chains 91 and 91a through the sprockets 95 and 96. Since the base member 126 is connected to the chains the base member together with the gripping elements composed of the jaws 121 and 35 131 will be moved in the direction indicated by the arrow in Fig. 1 whereby the woody portions of the stalks will be withdrawn from the bark and this bark will be retained on the clamping table 33. After the stalks have been removed they are 40 thrown to one side and the bell crank 110 is shifted in the opposite direction so that the chains will be driven in a reverse path for returning the base member 126 and the jaw 121 back to the initial position for clamping the ends of 45 the shells of the bark between the jaw 121 and the next uppermost gripping jaw 131a. The jaw 131 which was employed for gripping the woody portion of the stalks in connection with the jaw 131 is removed at the end of the machine and is 50 again returned to the vertically disposed guide members 133.

55 As has been explained each gripping jaw 131 is connected to the base member 126 through the automatic catches 141 and 142. The jaws 131 are also held in horizontal alignment with the base member 126 by the projections 146 which extend forwardly of the base member 126. Figs. 10 to 15, inclusive, show the various steps for drawing the bark through the rollers 165 and 60 166 and these rollers have roughened surfaces for removing the dark portions of the bark from the shells of the bark after the woody portion has been removed. As shown in Fig. 12 the 65 bark per se of each stalk is clamped between the jaws 121 and 131 and the lever 110 is oscillated for throwing the proper gears into mesh to cause outward movement of the base member 126 and the cooperating jaws 121 and 131 which are 70 clamped on the bark. At this time the bark is pulled between the rollers as has been explained for the removal of the outer covering. During the drawing of the bark from the clamping table 33 the flat spring member 250, connected at 75 75

to the beams 20 and 21, will act as a support for the bark at this time.

The rollers 165 and 166 are positively driven by either the crank 172 revolving the gear 170 or 5 these gears may be power driven through the pulley 180, the gears 177-178 and the shaft 185. The gears may be reversely rotated by oscillating the arm 167 for causing the reversal of the rotation of the shaft 185 and likewise the gear 175.

10 The bark after the dark portions have been removed in this manner is then again placed in tanks and either boiled in clear water or a soapy solution for the removal of gum and the green coloring matter of the bark.

15 At no time during the process is the bark allowed to dry. Furthermore, fermentation is not allowed to set in because during such treatment the bark becomes mildewed and the fibers become discolored.

20 When the base member 126 reaches the roller 94 said base member will pass over the roller and be inverted unless the driving chains are stopped. If the base member 126 passes over and below the roller the gripping jaw 131 will be released from 25 its support and it will drop away from the machine. When this happens the chains are stopped by oscillating the bell crank 110 to a neutral position. Further oscillation of the bell crank will cause the chains to reverse the direction of movement and return the table to the initial position of 30 operation adjacent the clamping table. A basket may be placed below the roller 94 so that as the gripping jaws 131 are released they will fall in the basket and these jaws are then returned to 35 the guides 131 manually.

It will be noted that when the jaws 131 are drawn in the direction indicated by the arrow in Fig. 1 they are being supported at all times by the projections 146 which are received by the 40 slots 145 formed in the underfaces of the jaws 131. Therefore when the table is reversed in position as it travels over the roller 94 the gripping jaws 131 will no longer be supported and they will fall away from the machine.

45 I claim:

1. A decorticating machine comprising a slidably mounted clamping table, a movable means for clamping the bark covered stalks on the table, a stalk gripping means having a pair of clamping jaws spaced from one end of said table, means for moving the table towards the gripping means so that the adjacent ends of the woody portions 50 of the stalks may be clamped between the jaws of the gripping means, means retaining the table against further movement when located adjacent the gripping means, means causing the jaws to be clamped on to the ends of the stalks, and means moving the jaws away from the table and the woody portions of the stalks from the bark, 55 the bark being held on the table by the movable clamping means.

2. A decorticating machine comprising a slidably mounted clamping table, a movable means for clamping the bark covered stalks on the table, a stalk gripping means having a pair of clamping jaws spaced from one end of said table, means for moving the table towards the gripping means, said gripping means including stationary guides, 65 a removable jaw mounted in the guides, a movable base member, a second jaw pivoted on said base member, the adjacent ends of the woody portions of the stalks adapted to be clamped between the jaws, means retaining the jaws in clamped relation, cooperating means on the base 70 members and removable jaw for connecting said

jaw to the base member, and means causing the base member and jaws to be moved away from the table whereby the woody portions of the stalks are withdrawn from the bark clamped on the table.

3. A decorticating machine comprising a slidably mounted clamping table, a movable means for clamping the bark covered stalks on the table, a stalk gripping means having a pair of clamping jaws spaced from one end of said table, means for moving the table towards the gripping means, said gripping means including stationary guides, a removable jaw mounted in the guides, a movable base member, a second jaw pivoted on said base member, the adjacent ends of the woody portions of the stalks adapted to be clamped between the jaws, means retaining the jaws in clamped relation, interlocking catches on the base member and removable jaw for removably connecting said jaw to said base member, and means causing the base member and jaws to be moved away from the table whereby the woody portions of the stalks are withdrawn from the bark clamped on the table.

4. A decorticating machine comprising a 25 slidably mounted clamping table, a movable means for clamping the bark covered stalks on the table, a stalk gripping means having a pair of clamping jaws spaced from one end of said table, means for moving the table towards the gripping means, said gripping means including stationary guides, a removable jaw mounted in the guides, a movable base member, a second jaw pivoted on said base member, the adjacent ends of the woody portions of the stalks adapted 30 to be clamped between the jaws, means retaining the jaws in clamped relation, catch members on the base member and removable jaw adapted to automatically interlock when the base member is moved into operative position with the removable jaw.

5. A decorticating machine comprising a slidably mounted clamping table, a movable means for clamping the bark covered stalks on the table, a stalk gripping means having a pair of 45 clamping jaws spaced from one end of said table, means for moving the table towards the gripping means, said gripping means including stationary guides, a plurality of removable jaws located in the guides, a base member, a pivoted jaw on the base member, a spring urging the uppermost jaw into horizontal alinement with the base member, cooperating means on the base member and a removable jaw for connecting the jaw to the base member, means causing the pivoted jaw to clamp the ends of the woody portions of the stalks on to the uppermost removable jaw and means moving the jaws and base member away from the table for withdrawing the woody portions out of the bark retained on the clamping table.

6. A decorticating machine comprising a slidably mounted clamping table, a movable means for clamping the bark covered stalks on the table, a stalk gripping means having a pair of 65 clamping jaws spaced from one end of said table, means for moving the table towards the gripping means, said gripping means including stationary guides, a removable jaw mounted in the guides, a movable base member, a second jaw pivoted on said base member, the adjacent ends of the woody portions of the stalks adapted to be clamped between the jaws, means retaining the jaws in clamped relation, cooperating means on the base members and removable jaw for con- 70

necting said jaw to the base member, and means causing the base member and jaws to be moved away from the table whereby the woody portions of the stalks are withdrawn from the bark 5 clamped on the table, and means for causing the moving means for the base member to return to its initial position.

7. A decorticating machine comprising a slidably mounted clamping table, a movable 10 means for clamping the bark covered stalks on the table, a stalk gripping means having a pair of clamping jaws spaced from one end of said table, means for moving the table towards the gripping means so that the adjacent ends of the 15 woody portions of the stalks may be clamped between the jaws of the gripping means, means causing the jaws to be clamped onto the ends of the stalks, and means moving the jaws away from the table and the woody portions of the 20 stalks from the bark, the bark being held on the table by the movable clamping means, means for causing the moving means for the jaws to return said jaws to the clamping table after the woody portions of the stalks have been released, 25 said gripping jaws adapted to clamp the adjacent ends of the bark therebetween, roughing rollers through which the bark is drawn.

8. A decorticating machine comprising a slidably mounted clamping table, a movable 30 means for clamping the bark covered stalks on the table, a stalk gripping means having a pair of clamping jaws spaced from one end of said table, means for moving the table towards the gripping means so that the adjacent ends of the 35 woody portions of the stalks may be clamped between the jaws of the gripping means, means causing the jaws to be clamped onto the ends of the stalks, and means moving the jaws away from the table and the woody portions of the stalks from the bark, the bark being held on the table by the movable clamping means, rods connected to the movable 40 clamping means, guides for the rods, a pivotally mounted treadle, means connecting the ends of the rods to the treadle for forcing the clamping 45 means onto the table.

9. A decorticating machine comprising a slidably mounted clamping table, a movable means for clamping the bark covered stalks on the table, a stalk gripping means having a pair of 50 clamping jaws spaced from one end of said table, means for moving the table towards the gripping means, said gripping means including stationary guides, a removable jaw mounted in the guides, a movable base member, a second 55 jaw pivoted on said base member, the adjacent ends of the woody portions of the stalks adapted to be clamped between the jaws, means retaining the jaws in clamped relation, cooperating means on the base members and removable jaw 60 for connecting said jaw to the base member, and means causing the base member and jaws to be moved away from the table whereby the woody portions of the stalks are withdrawn from the bark 65 clamped on the table, and tracks for guiding the base member and connected removable jaw in the same plane.

10. A decorticating machine comprising a slidably mounted clamping table, a movable means for clamping the bark covered stalks on the table, 70 75 a stalk gripping means having a pair of clamp-

ing jaws spaced from one end of said table, means for moving the table towards the gripping means said gripping means including stationary guides, a removable jaw mounted in the guides, a movable base member, a second jaw pivoted on said base member, the adjacent ends of the woody portions of the stalks adapted to be clamped between the jaws, means retaining the jaws in clamped relation, cooperating means on the base members and removable jaw for connecting said jaw to the base member, and means causing the base member and jaws to be moved away from the table whereby the woody portions of the stalks are withdrawn from the bark 5 clamped on the table, the removable jaw being 10 provided with transverse slots, the base member having extensions adapted to project into the slots when said jaw is connected to the base member.

11. A decorticating machine comprising a slidably mounted clamping table, a movable means 20 for clamping the bark covered stalks on the table, a stalk gripping means having a pair of clamping jaws spaced from one end of said table, means for moving the table towards the gripping means so 25 that the adjacent ends of the woody portions of the stalks may be clamped between the jaws of the gripping means, means causing the jaws to be clamped onto the ends of the stalks, and means moving the jaws away from the table and the 30 woody portions of the stalks from the bark, the bark being held on the table by the movable clamping means, rods connected to the movable clamping means, guides for the rods, a pivotally mounted treadle, means connecting the ends of 35 the rods to the treadle for forcing the clamping means onto the table.

12. A decorticating machine comprising a slidably mounted clamping table, a movable means for clamping the bark covered stalks on the table, 40 a stalk gripping means having a pair of clamping jaws spaced from one end of said table, means for moving the table towards the gripping means so that the adjacent ends of the woody portions of the stalks may be clamped between the jaws of the 45 gripping means, means causing the jaws to be clamped on to the ends of the stalks, and means moving the jaws away from the table and the woody portions of the stalks from the bark, the bark being held on the table by the movable 50 clamping means, rods connected to the movable clamping means, guides for the rods, a pivotally mounted treadle, means connecting the ends of the rods to the treadle for forcing the clamping 55 means onto the table, and means retaining the movable clamping means in clamped position on the table.

13. A decorticating machine comprising a slidably mounted clamping table, a movable means for clamping the bark covered stalks on the table, a 60 stalk gripping means having a pair of clamping jaws spaced from one end of said table, means for moving the table towards the gripping means so that the adjacent ends of the woody portions of the stalks may be clamped between the jaws of the 65 gripping means, means causing the jaws to be clamped onto the ends of the stalks, and means moving the jaws away from the table and the woody portions of the stalks from the bark, the bark being held on the table by the movable 70 clamping means, means for causing the moving means for the jaws to return said jaws to the clamping table after the woody portions of the stalks have been released, said gripping jaws adapted to clamp the adjacent ends of the bark 75

therebetween, roughing rollers through which the bark is drawn, means hingedly mounting one of the rollers so that it will swing away from the other roller, and means for revolving the rollers.

5 14. A decorticating machine comprising a slidably mounted clamping table, a movable means for clamping the bark covered stalks on the table, a stalk gripping means having a pair of clamping jaws spaced from one end of said table, means for 10 moving the table towards the gripping means, said gripping means including stationary guides, a removable jaw mounted in the guides, a movable base member, a second jaw pivoted on said base member, the adjacent ends of the woody portions 15 of the stalks adapted to be clamped between the jaws, means retaining the jaws in clamped relation, cooperating means on the base members and removable jaw for connecting said jaw to the base member, and means causing the base member 20 and jaws to be moved away from the table whereby the woody portions of the stalks are withdrawn from the bark clamped on the table, a U-shaped member pivotally mounted on the base member and having the free ends of the legs thereof connected 25 to the pivoted jaw.

15. A decorticating machine comprising a slidably mounted clamping table, a movable means for clamping the bark covered stalks on the table, a stalk gripping means having a pair of clamping jaws spaced from one end of said table, means for moving the table towards the gripping means, said gripping means including stationary guides, a removable jaw mounted in the guides, a movable base member, a second jaw pivoted on said base member, the adjacent ends of the woody portions 10 of the stalks adapted to be clamped between the jaws, means retaining the jaws in clamped relation, cooperating means on the base members and removable jaw for connecting said jaw to the base member, and means causing the base member and jaws to be moved away from the table whereby the woody portions of the stalks are withdrawn from the bark clamped on the table, a U-shaped member 15 pivotally mounted on the base member and having the free ends of the legs thereof connected to the pivoted jaw, a second U-shaped member slidably mounted on the first U-shaped member for releasing the retaining means for the pivoted clamping jaw.

JOSEPH JULIUS MARCZAK.
